UNITED STATES PATENT OFFICE

118,330

DESIGN FOR A BOTTLE

James M. Guthrie, Pittsburgh, Pa., assignor of one-half to Joseph C. Keaney, Mount Lebanon, Pa.

Application December 3, 1938, Serial No. 81,545

Term of patent 14 years

To all whom it may concern:

Be it known that I, James M. Guthrie, a citizen of the United States, residing at Pittsburgh, in the county of Allegheny and State of Pennsylvania, have invented a new, original, and ornamental Design for a Bottle, of which the following is a specification, reference being had to the accompanying drawing, forming part thereof.

In the drawing—

Fig. I is a view in rear elevation, and Fig. II is a view in front elevation of a bottle showing the new design; and Fig. III is a view of the bottle in cross section, on the plane III—III of Fig. II.

The application for this patent comprises a continuation in part of application Serial No. D77,861, filed June 16, 1938.

I claim:

The ornamental design for a bottle, substantially as shown.

JAMES M. GUTHRIE.
